TRIM PANEL FOR AN AUTOMOBILE

Edward H. Ziner, Upper Marlboro, Md., and Carl E. Fischer, 7655 Lombard St., Kentland, Md.

Filed Dec. 24, 1962, Ser. No. 72,934

Term of patent 14 years

(Cl. D14—6)

FIG. 1 is a perspective view of a trim panel for an automobile, showing our new design.

FIG. 2 is a side view of the trim panel for an automobile shown in FIG. 1.

FIG. 3 is a rear view of the trim panel for an automobile shown in FIG. 1.

FIG. 4 is a vertical, transverse sectional view taken along the line 4—4 in FIG. 2.

The portions shown in broken lines are included for illustrative purposes only.

We claim:

The ornamental design for a trim panel for an automobile, as shown and described.
